UNITED STATES PATENT OFFICE.

CHARLES SPIRO, OF NEW YORK, N. Y., ASSIGNOR TO FEDERAL ADDING MACHINE CORPORATION, OF NEW YORK, N. Y., A CORPORATION OF NEW YORK.

BELL RINGER AND LINE LOCK.

1,410,773.

Specification of Letters Patent. Patented Mar. 28, 1922.

Original application filed September 7, 1920, Serial No. 372,070. Divided and this application filed January 12, 1921. Serial No. 436,707.

To all whom it may concern:

Be it known that I, CHARLES SPIRO, a citizen of the United States, residing at New York, in the county of New York and State 5 of New York, have invented certain new and useful Improvements in Bell Ringers and Line Locks, of which the following is a specification.

This invention relates to a bell ringer and 10 line lock and comprises a division of my application filed September 7, 1920, Serial No. 372,070 for carriage control mechanism.

The invention has for an object to provide 15 a novel and improved construction in which the bell hammer is directly actuated by the carriage stop to ring a bell in its preliminary movement and a further actuation thereof causes the hammer to directly engage a line lock mechanism.

20 Another object of the invention is to present a new structure of unit for controlling the bell, line lock, and margin abutment and adapted for unitary release of these parts.

A further object of the invention is to provide 25 an improved form of carriage stop adapted to cooperate with a flanged collar to rotate the same to different extents for the successive actuation of the bell ringer and line lock.

30 Other and further objects and advantages of the invention will be hereinafter set forth and the novel features thereof defined by the appended claims.

In the drawings—

35 Figure 1 is a front elevation of the invention applied;

Figure 2 is a vertical section on line 2—2 of Figure 1;

40 Figure 3 is a detail perspective of the actuating collar; and

Figure 4 is a similar view of a carriage stop.

Like numerals refer to like parts in the several figures of the drawings.

45 The numeral 10 designates the frame of a typewriter, which may be of any desired construction or configuration, and supports the usual carriage 11 provided with a platen 12. At the front of the top plate 13 of the

50 frame a supporting rod 14 is pivotally mounted in any desired manner and carries tabulator abutments 17, the leftmost member 18 thereof being secured to the rod as dis-

closed in my application filed September 7, 1920, Serial No. 372,070.

55

The rod 14 also carries a collar 60 which forms a unit for the margin abutment, bell-ringing and line lock connections. The end of this collar next the tabulator abutment 18 is provided with a pivoting slot 61 to receive 60 the pivots 62 of the margin abutment 63 which is of yoke shape to embrace the collar. The abutment is also provided with a lateral arm 65 which carries a curved spring 66 resting upon the upper face of the collar. 65 This margin abutment rests against the tabulator abutment 18 when in operative position and the latter receives the impact upon contact with a carriage stop in the travel of the carriage toward the right. In the carriage movement toward the left the margin abutment yields upon its pivot against the tension of its spring to permit the stop to pass.

70 For the purpose of rocking the collar to release the margin abutment or the line lock it is provided with a rib 68 having at one face a contact 69 disposed to be engaged by a release lever 70. This lever is formed with a collar 71 mounted upon a pivot 27 and 75 deflected arm 72 having a pivotal connection with a sliding margin release key 73 mounted in a suitable support at the front of the typewriter.

75 The collar 60 is also provided with a cam face or flange 75 disposed in a plane to be actuated by a bell and lock stop 76 mounted upon the carriage. This stop is slidingly mounted upon a rod 51 carried by the arms 52 of the carriage frame and comprises parallel side walls 53 extended beneath a rack 54 and adapted to engage the teeth 55 thereof. The stop is normally retained in such engagement by a spring 56 secured thereto and bearing against the inner face of the 85 rack. The stop is also formed with a finger piece 57 for its disengagement from the rack and an indicating finger 58 to cooperate with an indicating scale 59 upon the upper face of the rack. The carriage stop 22 for the 90 margin abutment is similar in construction to the stop so far described, but the bell and lock stop is provided with depending contacts 77 and 78 of different lengths to successively impart different degrees of oscillation to the collar 60 at spaced intervals.

95

100

105

At the opposite end of the collar from the flange 75 a bell ringing arm 79 is secured and in the present instance comprises a bell hammer 80 adapted to contact with a bell 81 carried by a bracket 82 upon the machine frame in the usual manner. When the flange 75 contacts with the stop 77 the collar is rocked to such an extent as to withdraw the bell hammer to the position indicated by dotted lines in Figure 2, and as the flange leaves the stop 77 the hammer is restored or thrown into contact with the bell by any desired form of spring, such as shown at 83. In the continued movement 10 of the bell and lock stop, the face 78 thereof further depresses the cam flange and rocks the bell hammer to a greater extent so as to contact with the face 84 of the rock lever 85 which is pivoted at 86 upon a fixed support 15 87. The lower end 88 of this rock lever carries a pivoted link 89 extending to an arm 90 upon the axis of a pivoted locking bail 91 disposed beneath the locking face 92 of the key lever 93 mounted in the machine 20 frame in the ordinary manner. The locking lever is restored to inoperative position by a tension spring 94, as shown in Figure 2. If it be desired to release the line lock for further writing at this margin of the paper, 25 a depression of the margin release key rocks the cam flange to withdraw the hammer from the rock lever and the spring thereon then releases the bail from the key lever, while the spring upon the hammer 30 constantly tensions the same into inoperative 35 position.

It will be seen that this construction provides for the direct operation of the bell hammer by the carriage stop and the subsequent direct actuation by the hammer of the line lock. This simplifies the structure and dispenses with the connecting parts used in the prior art so as to secure a positive operation with the minimum of friction and 45 maximum of efficiency.

The unit construction provides a single member for controlling the bell ringer, line lock and margin abutment and such member adapted for the release of either said abutment or the line lock. While the invention 50 has been designed for application at the front of a typewriter above the key board thereof it may be otherwise disposed thereon. The bell and lock stop for the carriage 55 is particularly adapted to cooperate with rocking control collar herein disclosed.

While the specific construction of this mechanism has been shown and described, still the invention is not confined thereto, as 60 changes and alterations may be made therein without departing from the spirit of the invention.

What I claim is—

1. In a typewriter, a frame, a carriage 65 thereon, a support upon the frame, a collar

pivoted upon said support and provided with an actuating flange, a bell hammer carried by said collar, a line lock device having a member disposed in the path of travel of said hammer, and means upon the carriage to engage said flange. 70

2. In a typewriter, a frame, a carriage thereon, a support upon the frame, a collar pivoted upon said support and provided with an actuating flange, a bell hammer carried by said collar, a line lock device having a member disposed in the path of travel of said hammer, a margin abutment carried by said collar, means upon the carriage to engage said flange and abutment, and a key 75 connected to rock said collar to release either said line lock or abutment.

3. In a typewriter, a frame, a carriage mounted thereon and provided with a bell and lock stop, a support upon the frame, a 85 collar pivoted upon said support and provided with a cam flange disposed in the path of travel of said stop, a bell engaging member carried by said collar, a line lock device having a part disposed in the path 90 of said bell engaging member, contacts upon said stop to actuate said cam for different degrees of travel, and means to rock said collar flange out of the path of said contacts. 95

4. In a typewriter, a frame, a carriage mounted thereon and provided with a bell and lock stop, a support upon the frame, a collar pivoted upon said support and provided with a cam flange, a bell hammer carried by said collar, a line lock lever disposed in the path of said hammer, contacts upon said stop disposed to successively actuate said cam for different degrees of travel, and a release key connected to rock said collar 100 and flange out of the path of said contacts. 105

5. In a typewriter, a frame, a carriage mounted thereon, a bell and lock actuating unit movably mounted upon the frame, a bell engaging member from said unit, a line locking device disposed in the path of said member to be actuated thereby, and means upon the carriage for successively imparting different degrees of movement to 110 said unit. 115

6. In a typewriter, a frame, a carriage mounted thereon, a stop upon the carriage, a bell and lock actuating unit movably mounted upon the frame, a bell engaging member from said unit, a line lock lever having one end in the path of said member, a key lever, a pivoted bail beneath the same, and a link connecting an arm from said bail with said lock lever. 120

7. In a typewriter, a frame, a carriage 125 mounted thereon, a stop upon the carriage, a bell and lock actuating unit movably mounted upon the frame, a bell engaging member from said unit, means for tensioning said member toward the bell, a line lock 130

lever having one end in the path of said member, means for tensioning said lever toward said member, a key lever, a pivoted locking bail beneath the same, and a link 5 connecting said bail with said lock lever.

8. In a typewriter, a frame, a carriage mounted thereon, a stop upon the carriage, a cooperating bell and lock actuating unit movably mounted upon the frame, a bell 10 hammer carried by said unit, a line lock lever having a contact face at its upper end disposed in the path of said hammer, a key lever provided with a depending locking face, a swinging locking bail disposed beneath said key lever and having an actuating arm, and a link connecting said arm and lock lever.

9. In a typewriter, a frame, a carriage mounted thereon, a bell upon the frame, a bell 20 and lock actuating unit thereon, a bell striking member carried by said unit, a line locking device having a part in the path of said member, and a stop device upon the carriage having contact faces of different 25 lengths to successively engage said actuating unit.

10. In a typewriter, a frame, a carriage mounted thereon, a rocking locking unit upon the frame provided with a cam flange 30 and a depending arm, a bell disposed to be engaged by said arm, a line locking device disposed to be engaged by said arm, and a stop device upon the carriage having spaced contact faces of different lengths to successively engage said flange.

11. In a typewriter, a frame, a carriage mounted thereon, a rocking collar upon the frame, a bell ringing and line lock member carried by said collar, means upon the carriage for rocking said collar, a release lever upon the frame engaging said collar, and a sliding release key pivotally connected to said lever.

12. In a typewriter, a frame, a carriage mounted thereon, a rocking collar upon said frame, a bell ringing and line lock member carried by said collar, a margin abutment pivoted to said collar and provided with a lateral arm, a restoring spring carried by 50 said arm to engage said collar, a contact face upon said collar, and a release key connected to engage said face.

13. In a typewriter, a bell and lock stop comprising a body having an upwardly disposed rack tooth and depending spaced parallel contacts of successively increasing lengths.

14. In a typewriter, a bell and lock stop comprising a slidable body having rack engaging walls and horizontal extensions therefrom provided with depending contacts of increasing lengths.

15. In a typewriter, a carriage frame provided with a slide rod, a rack member disposed parallel thereto and having indica-

tions upon its upper face and teeth upon the lower face thereof, a stop mounted upon said rod and having a wall to engage said teeth and a pointer to cooperate with said indications, and spaced depending bell and 70 lock contacts carried by said stop.

16. In a typewriter, a bell and lock actuating unit comprising a collar having at one end a cam flange and release lug and at its opposite end an angularly disposed bell and 75 lock member.

17. In a typewriter, a bell and lock actuating unit comprising a collar having at one end a cam flange and release lug and at its opposite end an angularly disposed bell and 80 lock contact member, a margin abutment pivoted upon said collar, and a restoring spring carried thereby and bearing upon said collar.

18. In a typewriter, a pivoted bell and 85 lock unit having a depending hammer arm, carriage controlled means for swinging said arm for different extents of travel, a bell disposed in the path of the free end of said arm at one side thereof, and a line lock device 90 disposed in said path at the opposite side of said arm end.

19. In a typewriter, a frame, a carriage thereon, a supporting member at the front of the frame, a tabulator abutment carried 95 by said member, a unit mounted upon said member and provided with a margin abutment disposed to engage the tabulator abutment, bell ringing and line lock actuating means upon said unit, and means upon the 100 carriage cooperating with the several means carried by said unit.

20. In a typewriter, a frame, a carriage thereon provided with a margin stop, a rod mounted upon said frame, a collar pivoted 105 on said rod, a margin abutment pivoted on said collar and spring held in operative position, an abutment member carried by said rod to be engaged by said margin abutment, and means for rocking said collar. 110

21. In a typewriter, a frame, a carriage thereon provided with a margin stop, a rod mounted upon the frame, a collar pivoted upon said rod, a margin abutment pivoted on said collar and spring held in operative 115 position, a tabulator member carried by said rod to be engaged by the margin abutment when in operative position, and means for rocking said margin abutment out of the path of the carriage stop. 120

22. In a typewriter, a frame, a carriage control unit supported thereon, a margin abutment yieldingly mounted on said unit, a tabulator abutment member carried by a sleeve secured to said frame and engaging the margin abutment when in vertical position, and means for actuating said abutment members.

In testimony whereof I affix my signature.
CHARLES SPIRO.
